Inventor
Amos Fales,

By his Attorney, J. S. Brown.

UNITED STATES PATENT OFFICE.

AMOS FALES, OF ROCK FALL, CONNECTICUT.

DESIGN FOR A BENCH-PLANE CUTTER.

SPECIFICATION forming part of Design No. 18,381, dated June 12, 1888.

Application filed July 16, 1887. Serial No. 244,551. Term of patent 14 years.

To all whom it may concern:

Be it known that I, AMOS FALES a citizen of the Dominion of Canada, residing at Rock Fall, in the county of Middlesex and State of Connecticut, have invented and produced a new and original Design for a Bench-Plane Cutter; and I do hereby declare that the following is a full and exact description thereof, reference being had to the accompanying drawing, making part of this specification, and representing a view of the cutter in perspective.

The leading features of my design consist in the V-shaped form of the cutting-edge, the under beveled sides, and in the forward inclination of the cutting-edge in side view when it is in position in the stock. The cutter part projects above and is thicker than the shank part, and the latter is rectangular in cross-section.

In the drawing, A represents the cutter entire, and *a a b* its cutting-edge. The form of this cutting-edge is that of the letter V, converging from the two upper extremities, *a a*, to the lower point, *b*. As seen in the drawing, the edge at the highest point, *a a*, is more advanced than any other part of the edge, and the lowest

point, *b*, is least advanced in the direction of the motion of the plane, and all the parts of the edge regularly recede in position as they are lower in position. Thus the upper parts take the wood or material in advance of the lower parts thereof. The lower angle of the cutter does not reach to the bottom or lower side of the body of the cutter; but the edge has beveled under sides, *c c*, leading back to the said lower side, as shown in the drawing. The shank *d* of the cutter is not so thick as the cutter part, which projects above the same. This shank is rectangular in cross-section.

I claim—

The design for a bench-plane cutter herein shown and described, which consists of the body A, rectangular in cross-section and flat on its under side throughout its length to the edge chamfers, with its upper surface lying in two planes, and having a V-shaped groove in the thicker part provided with cutting-edges *c c*, substantially as herein specified.

AMOS FALES.
